UNITED STATES PATENT OFFICE.

CARL GROSSE, OF BERLIN-HERMSDORF, GERMANY.

SAFETY DEVICE FOR ELECTRIC LINES.

Application filed June 12, 1925, Serial No. 36,746, and in Germany August 18, 1924.

Electric automatic safety devices are generally known, but hitherto in domestic installations fuses have almost exclusively been used for protecting electric lines. The 5 safety devices used hitherto have the drawback that, when they have been caused to act by the current becoming too strong, they must be unscrewed for being made operative again.

10 In the accompanying drawing:

Fig. 1 is the vertical section through the safety device according to the invention.

Figs. 2 and 3 are cross sections along line A—B, seen in the direction of the arrows 2, 3.

15 Figs. 4 and 5 are cross sections on line A—B seen in the direction of the arrows 4, 5.

In the drawing *a* is the casing of the safety device which is generally made of insulating material and which extends into a socket 20 which is screwed-in; *b* is a cover with a cylindrical projecting part which is rotatably arranged in the casing. On the front side of the extended part a contact disc *b*¹ is fixed, having an adjoining part *b*². The 25 latter is extended to form a contact strip *d*, which is arranged on the circumference of the cylindrical adjoining or projecting part. On the cover *b* there is further a pin *s* arranged, which protrudes from the cover, and, 30 further a pin *n*, which serves as axle or shaft.

In the interior of the casing, in the longitudinal direction of the same, and preferably arranged in a cavity or recess, a contact strip *d*¹ is arranged which may be 35 formed by a piece of wire leading down to the metal part of the socket and conductively connected with it. This contact strip may be covered towards the interior by an insulating strip *i*.

40 In the casing *a* there is arranged a cylinder *e* formed of insulating material and rotatable about a pin and having a recess or cavity for receiving a tension spring *f*. This spring *f* is fixed with the one end to the cylinder *e* and with the other end to a point

45 in the casing *a*, for instance, by a plate *g*, which is secured in the casing *a* against rotation. In the front side of the cylinder *e* there is fixed a contact disc *e*¹ with a lug *e*². The contact disc *e*¹ is in constant contact with the contact disc *b*¹. The lug *e*² is extended into a contact strip *d*² which is arranged on the circumferential face of the cylinder *e*. This contact strip *d*² can come 50 in touch with the longitudinal contact strip *e*³ in certain positions of the cylinder *e*, the

longitudinal strip *d*³ being arranged in the casing *a*. On the other side of the cylinder *e* and within the casing *a*, a pawl or catch *r* is rotatably mounted on a pin *o*, said pawl *r* being influenced or actuated by a spring *t* and adapted to engage a recess *u* in the cylinder *e*. *p* is a fixing pin for the spring *t*.

g is an iron core within an electromagnetic coil *h*. The latter is connected on the one side to the contact strip *d*³ and on the other side by a conductor *m* to a contact screw *k* in the socket.

The cylinder *e* is provided with a semi-circular groove *l* which is engaged by the pin *s* of the cover *b*. When the electric current has such magnitude that a switching-out by the safety device is effected, the pawl or catch *r* is pulled out by the electromagnetic coil from the recess *u* against the action of the spring *t*, and the cylinder *e* is turned under the influence of the spring *f* approximately 180°, whereby the contact is interrupted between the contact strips *d*² and *d*³.

55 In order to switch-in the safety device again, one proceeds as follows:

The cover *b* is at first turned around 180° and during this rotary movement the pin *s* engaging the groove *l* of the cylinder *e*, entrains the cylinder until the pawl or catch *r* comes into engagement under the action of the spring *t*, with the recess *u* thereby locking the cylinder *e* in such position, in which the contact strips *d*² and *d*³ are in contact with each other. During this rotary movement the contacts *d*¹ and *d*² are interrupted so that during the adjusting of the cylinder *e* the circuit remains temporarily 60 interrupted. In order to finally close the circuit, it is necessary to turn the cover *b* back into its initial position so that the contacts *d* and *d*¹ are again in contact. The electric current flows in this case as follows: *k*, *m*, *h*, *d*³, *d*², *e*², *e*¹, *b*¹, *b*², *d*, *d*¹ to the metal parts of the socket.

65 If, however, at the moment when the cover *b* is returned into the initial position and the contacts *d* and *d*¹ are contacting again, and a still stronger current prevails, the pawl is immediately withdrawn and by the rotation of the cylinder *e* the contact between *d*² and *d*³ is interrupted.

70 With particular reference to Fig. 2 and Fig. 4 it is to be noted that there is shown the position of the cover *b* and of the cylinder *e* in the contact position of the safety

device, while Figs. 3 and 5 show that position of the parts when the safety device has interrupted the contact of the electric current thru the safety device.

5 It is never possible for the discs to be so set from the outside that the current can flow through them without their immediately breaking contact on the maximum current being exceeded, as with respect to the contacts $d-d^1$ and d^2-d^3 only the first-named contact connection can be secured, as this occurs, when by turning the cover, the safety device is again brought into the operative position, the other contact d^2-d^3 however remains constantly free for immediate disconnection under the action of the excessive current. On the other hand, the contact strips $d-d'$ are not in contact with one another when by turning the cover by hand, 10 through the medium of the pin s , the part e is turned until the contacts d^2-d^3 come in contact with one another. Fig. 1 shows the operative position of the cover and the part e , the part e being always disconnected by 15 excessive current without it being possible to prevent this externally.

What I claim is:—

1. An automatic safety device for electric lines, comprising in combination a casing 30 of insulating material, a socket on the said casing, a rotatable contact member in the said casing, a second rotatable contact member in the casing, a spring capable of acting on the second contact member and of turning 35 the same when free to move, a semi-circular groove in the second contact member, a pin on the first contact member for engaging in the said groove for coupling the two contact members, contact arcs on the surfaces 40 facing each other of the two contact members, each arc forming a lateral contact on the contact member, on which it is mounted, a solenoid located in the casing, securing means for the second contact member, 45 capable of being acted on by the said solenoid, a spring capable of acting on the securing means for securing the second contact member, a connecting lead from the solenoid to a contact member at the bottom 50 of the safety device, a contact strip connected to the solenoid and extending laterally from the second contact member, a contact strip in the casing extending from the first contact member to the socket of 55 the safety device and means for turning the first contact member.

2. An automatic safety device for electric lines, comprising in combination a casing

of insulating material, a socket on the said casing, a rotatable contact member in the said casing, a second rotatable contact member in the casing, a spring capable of acting on the second contact member and of turning the same when free to move, a semi-circular groove in the second contact member, a pin on the first contact member for engaging in the said groove for coupling the two contact members, contact arcs on the surfaces facing each other of the two contact members, each arc forming a lateral contact on the contact member, on which it is mounted, a solenoid located in the casing, a detent arrangement capable of engaging in the second contact member, a spring capable of acting on the detent arrangement, 75 a connecting lead from the solenoid to a contact member at the bottom of the safety device, a contact strip connected to the solenoid and extending laterally from the second contact member, a contact strip in the 80 casing extending from the first contact member to the socket of the safety device and means for turning the first contact member.

3. An automatic safety device for electric lines, comprising in combination a casing of 85 insulating material, a socket on the said casing, a rotatable contact member in the said casing, a second rotatable contact member in the casing, a spring capable of acting on the second contact member and of turning 90 the same when free to move, a semi-circular groove in the second contact member, a pin on the first contact member for engaging in the said groove for coupling the two contact members, contact arcs on the surfaces facing each other of the two contact members, each arc forming a lateral contact on the contact member, on which it is mounted, a solenoid located in the casing, a fixed iron core in the casing, a pivoted detent capable 95 of engaging in the second contact member, when the latter is in a certain position, a spring capable of acting on the said detent, a connecting lead from the solenoid to a contact member at the bottom of the safety 100 device, a contact strip connected to the solenoid and extending laterally from the second contact member, a contact strip in the casing extending from the first contact member to the socket of the safety device 105 and means for turning the first contact member.

In testimony whereof I have signed my name to this specification.

CARL GROSSE.
